OF NEW YORK, N. Y., A CORPORATION OF DELAWARE.

LOCOMOTIVE-BOILER FURNACE.

1,160,484.

Specification of Letters Patent. Patented Nov. 13, 1915.

Original application filed December 18, 1911, Serial No. 666,337. Divided and this application filed March 24, 1915. Serial No. 16,694.

To all whom it may concern:

Be it known that I, CHARLES B. MOORE, a citizen of the United States, and a resident of the city of Evanston, county of Cook, and 5 State of Illinois, have invented certain new and useful Improvements in Locomotive-Boiler Furnaces, of which the following is a specification.

My invention relates to improvements in 10 locomotive boiler furnaces and has special reference to refractory baffles or arches for the fireboxes of locomotive boilers.

This application is a division of my co-pending application, Serial No. 666,337, filed 15 December 18, 1911.

The general objects of my invention are to provide an improved refractory arch which may be easily and quickly installed in locomotive fireboxes; to provide an arch 20 which shall be comparatively light in weight and of low cost; to provide an arch which shall be easy to repair and parts of which may be readily removed to afford easy access to the firebox sides and flue sheet; and to 25 provide an arch which in a practical sense shall assist in commingling, admixing, and igniting the firebox gases and other combustibles.

My invention consists in the several improvements, the various constructions, and the combinations and relations of parts hereinafter set forth and particularly pointed out in the appended claims; and will be 30 readily understood upon reference to the 35 accompanying drawings.

In these drawings which form a part of this specification: Figure 1 is a longitudinal central sectional view of the locomotive boiler fire box and arch embodying my invention; Fig. 2 is a transverse vertical sectional view of the fire box on the line 2—2 of Fig. 1; Fig. 3 is a detail sectional view of the arch on the line 3—3 of Fig. 1; and Fig. 4 is a perspective view of one of the 45 side bricks.

I have illustrated my invention as embodied in the form of a so-called front arch, the particular function of which is to deflect the fire box gases as they rise from the 50 fuel bed and force them to travel to the rear end of the fire box instead of directly to the flues. This form of arch also assists in distributing the heat of combustion throughout

the fire box and particularly to the crown sheet. My improved arch is particularly 55 adapted for installation in fire boxes which are equipped with a number of longitudinally arranged water-circulating tubes. I build my arches of a number of individual bricks of a size that may be handled easily 60 and that may be passed through the fuel door.

A locomotive boiler fire box, as shown, consists of a flue sheet 2, side sheets 3—3, a crown sheet 4, and a rear sheet 5. A grate 6 65 is provided in the lower part of the fire box and flues 7 lead forward from the flue sheet. The rear sheet is provided with a fuel door or opening 8 and the fire box itself is positioned within the shell 9 of the locomotive 70 boiler, and I employ therein water-circulating arch tubes 10, the same extending from the lower portion of the flue sheet to the upper portion of the rear sheet. In the embodiment of my invention illustrated, I 75 employ four of these tubes 10.

I build my preferred form of arch of two brick patterns or forms *a* and *b*. The bricks *a* form the central or main portion of the arch, and are supported at their ends upon 80 adjacent tubes 10. The bricks *b* are arranged between the two outer tubes and the corresponding side sheets of the fire box. I support their outer ends upon studs or projections *b*² which I secure to the side sheets 85 of the fire box below the plane occupied by the tubes 10, so that I can incline the bricks *b* downwardly. I arrange them in downwardly and outwardly inclined positions and I provide their upper ends with 90 sockets *b*¹ which fit upon the tubes. As these bricks do not sustain any great weight, I make their outer ends relatively thin and I am thus enabled to make these bricks of relatively light weight. I prefer to taper 95 them in thickness from the thin outer ends to their thicker inner ends, this form resulting in a brick which is sufficiently strong and yet of light weight.

The bricks *a* are preferably provided 100 with relatively large recesses or pockets in their upper sides whereby they are considerably lightened in weight. The arch, as thus constructed, presents a central main portion which is substantially flat and the 105 height of which is dependent upon the

height of the tubes upon which these bricks rest, and a side or wing portion depending downwardly from the side edges of the main arch to the side sheet, the result being that to this extent the space beneath the tubes is decreased and the space above the tubes is increased. I preferably make the bricks *a* inwardly beveled upon their ends whereby they contact with the tubes so that these bricks will depend between the tubes to a certain extent and wedgingly engage them. I also preferably make the upper faces of the bricks of such length that the upper edges of their adjacent ends contact with each other when placed in position upon the tubes, that is, the upper faces of these bricks are practically equal in length from center to center of the tubes 10. Preferably the upper edges of the upper ends of the side bricks are beveled to correspond with the adjacent ends of the bricks *a*, and contact therewith, thereby relieving the tube to some extent of the spreading or wedging action of the main bricks, thereby assisting in maintaining the arch in true condition.

In order to provide a tight joint between the outer ends of the side bricks and the side sheets, I bevel the outer ends of the side bricks to correspond with the inclination of these bricks, as shown, so that the outer ends thereof are formed at an acute angle to the bottoms of the bricks and they abut substantially flat against the side sheets, thus effectively preventing the escape of the gases upwardly along the side sheets at the ends of these bricks or, in other words, at the side edges of the arch.

In building or installing arches which embody my invention, I place a row of the bricks *a* upon the lower ends of the tubes 10 and against the flue sheet, the number of bricks being determined by the number of tubes. I complete this first transverse row by a pair of side bricks *b* which I place in outwardly and downwardly inclined positions upon the outermost tubes and upon corresponding lugs, then I place another transverse row of the bricks extending from side sheet to side sheet, continuing the building of the arch until I have an arch of sufficient length to accomplish the desired results.

The downwardly inclined side or wing bricks are particularly useful in fire boxes, such as shown, wherein the main bricks *a* do not tend to severely spread the arch tubes, and consequently the side bricks may be light in weight. The form of side bricks shown, each having a comparatively thin edge abutting the side sheets, results in these bricks being relatively light and as they are inclined downwardly and outwardly,

they provide the arch with edges which are low upon the side sheets.

As many modifications of my invention will readily suggest themselves to one skilled in the art, I do not limit or confine my invention to the specific structures herein illustrated and described.

Having thus described my invention, I claim as new and desire to secure by Letters Patent:

1. A locomotive boiler firebox as described, in combination with two longitudinally inclined water-circulating arch-tubes adjacent to opposite side sheets of the box, studs upon said side sheets substantially below respective tubes, and a row of downwardly and outwardly inclined refractory bricks between each tube and adjacent side sheet, each said brick having its inner end socketed upon the tube and its outer end supported by a said stud or studs and beveled for abutment with the side sheet. 75

2. A locomotive boiler firebox as described, in combination with two longitudinally inclined water-circulating arch-tubes adjacent to opposite side sheets of the box, studs upon said side sheets substantially below respective tubes, and a row of downwardly and outwardly inclined refractory bricks between each tube and adjacent side sheet, each said brick having its inner end socketed upon the tube and its outer end supported by a said stud or studs. 85

3. A locomotive boiler firebox as described, in combination with two longitudinally inclined water-circulating arch-tubes adjacent to opposite side sheets of the box, studs upon said side sheets substantially below respective tubes, a row of downwardly and outwardly inclined refractory bricks between each said tube and adjacent side sheet, each said brick tapering toward its outer end and having its inner end socketed upon the tube and its outer end supported by a said stud or studs, and a refractory arch body upon and between said tubes. 95

4. A side brick for locomotive arches, composed of refractory material, having one end socketed for support by an arch tube, tapered toward its other end and said other end being beveled for downwardly inclined abutment with a fire box side sheet, *i. e.*, having its end formed at an acute angle to its bottom. 100

In testimony whereof, I have hereunto set my hand this 20th day of March, 1915, in the presence of two subscribing witnesses.

CHARLES B. MOORE.
